UNITED STATES PATENT OFFICE

EDMOND G. DUPRÉE, OF RICHMOND HILL, NEW YORK, ASSIGNOR TO BOORUM & PEASE COMPANY, OF NEW YORK, N. Y., A CORPORATION OF NEW YORK

LOOSE LEAF BINDER

Application filed December 5, 1930. Serial No. 500,350.

This invention relates to loose leaf post binders having flexible posts which are normally held rigid by spring pressure. It is in the nature of an improvement upon the invention of Frederick C. Bingham upon which application for patent was filed in the United States Patent Office on December 3rd, 1930, as Serial Number 499,782.

The objects of the invention are to provide an improved flexible post and improved means of adjusting same in the clamping bars, as will appear from the specification and claims.

In the drawings,
15 Figure 1 is a cross-section through one end of the clamping bars of a loose leaf binder, showing one form of the novel post flexed and showing one method of retaining it in the binding bars;

20 Figure 2 is a section similar to Figure 1, through the other end of the clamping bars, showing a post in rigid position;

Figures 3 to 8 inclusive illustrate a device provided in one of the clamping bars for locking the post against displacement after it has been flexed at any desired point.

Figure 3 shows the locking device in top elevation, partly cut away;

Figure 4 shows a side elevation of the locking device, the dotted position showing the device unlatched;

Figure 5 is a vertical section through the latch on the line 5—5 of Figure 3;

Figures 6, 7 and 8 are perspective views 35 showing parts of the locking device;

Figure 9 shows the post of Figures 1 and 2 in section and with a modification of the means for attaching it to the lower clamping bar;

40 Figure 10 illustrates a binder having a modified form of post and a further modification of the means for securing the post in the lower clamping bar and of the means for locking it in the upper clamping bar;

45 Figure 11 shows an unflexed section of the improved post enlarged to show clearly the internal design of the detached sleeves;

Figure 12 is a side elevation of a detached 50 sleeve;

Figure 13 is a top elevation of a detached sleeve.

Figure 14 is a section similar to Figure 11, but showing the post flexed;

Figure 15 is an elevational view (with portions cut away) of the back of a binder embodying a modified form of post, in which the ends of the post are modified from the constructions of Figures 1 to 14 inclusive;

Figure 16 is a view similar to Figure 15, 60 but showing only one end of the clamping bars and the post flexed;

Figure 17 shows the post of Figure 16 rigid, and shows the end cap removed and the top binding bar in the act of being removed;

Figure 18 is a vertical section through the post of Figures 15, 16 and 17.

My improved posts 20 are supported in the lower clamping bar 21 and their upper 70 ends are slidingly received in the upper clamping bar 22, which they enter through an opening 23, and within which bar their free ends may be buried.

Each post 20 comprises a central flexible 75 member 24 and a series of independent members or detached sleeves 25 which are threaded upon the flexible member and which form the outside of the post throughout most of its length.

As illustrated, the detached sleeves are interfitting members, circular in cross-section, each of which has a neck or neck portion 26 and a flange 27. See especially Figures 11 to 14 inclusive. The internal diameter of the flange 27 is about the same as or a little larger than the external diameter of the neck portion in order that successive sleeves may be nested with the neck of one within the flanged portion of the next, as clearly shown 85 in Figure 11. The internal bore of the neck portion 26 is tapered outwardly toward the external edge of the neck, forming a bell-shaped bore, as shown at 28.

This construction aids in flexing the post by forming a curved seat for the central flexible member at the point where the post is bent. See Figure 14. The sleeves may be threaded on the central element either with the neck turned downward as shown in Fig- 90 95 100

ure 1 or turned upward as shown in Figure 9.

The flexible member may be of any suitable sort, such as a cord, rope or twisted wire, as illustrated in Figure 1, or a chain, as shown 5 at 29 in Figure 18.

At an end of the post, spring means 30 is associated with the flexible member and the sleeves. This spring exerts tension on the independent sleeve members causing them 10 normally to interfit or remain nested and thus hold the post rigid.

The post may be provided with one or more end sections to aid in associating the flexible member and the spring with the 15 sleeves. The post shown in Figure 1 is provided with a top end section 35, within the bore of which the spring 30 is housed. The lower end of top end section 35 is formed with a neck like that of a sleeve 25, so that 20 it may nest within the flange of the uppermost sleeve. Upon the upper end of section 35 may be screwed a suitable end cap 36. Within the bore of section 35 the lower end of spring 30 bears against the shoulder 37, 25 while the upper end of spring 30 bears against a ring 38 which is provided near the upper end of the flexible member. Ring 38 has a diameter enabling it to fit slidably 30 within the bores of section 35 and end cap 36. The end cap 36 has the same external diameter as the rest of the post, which allows the top clamping bar to be removed when the post is upright, simply by raising the clamping bar until the end cap passes through the 35 opening 23.

The post shown in Figure 1 is also provided with a lower end section 34, which has the same external diameter as the sleeves and which forms part of the outside of the post 40 immediately above the lower clamping bar 21. The upper end of section 34 has a flange like the flanges 27 of the detached sleeves 25 so that the neck 26 of one of the sleeves may nest in it. The lower end of the interior of 45 lower end section 34 may be screw-threaded and cooperate with a nut 33, secured within the clamping bar 21, to receive a screw 32 which is provided at the lower end of the flexible member 24.

50 The post may be secured to the lower clamping bar rigidly, as shown in Figures 1 and 15, or vertically yieldingly, as shown in Figure 9, for example.

In order to flex the post at any desired 55 point, the operator need only bring the sleeve 25, which is immediately below the point, into the opening 23 in the lower wall of the upper clamping bar, and then bend the post in the desired direction. This will exert 60 sufficient force against the tension spring to allow the flexing, whereupon the post can be flexed at right-angles so that the upper part of the post will lie horizontally. Upon being flexed the parts of the post will assume 65 the position shown clearly in Figure 14. In

the embodiment of the invention illustrated the post may be flexed in any direction.

Any suitable cover may be provided to retain the post in its flexed position. The form of cover 31 shown in Figs. 1-8 will be 70 described more fully below.

If desired, a flat spring 39 may be provided to project below the lower wall of the top clamping bar 22, to rest upon the loose leaves 40 when the binder is closed, and thus 75 aid in keeping the leaves compressed.

“The bent portion 49 of the spring 39 projects downwardly through an opening 50 in the lower wall of the upper clamping bar, while the free tip 51 of the spring rests within the clamping bar.” See Figures 2, 4 and 7.

When the post is flexed and its upper end is lying in the clamping bar, as shown in Figs. 1 and 16, for example, the post presses upon the free end of the spring 39 and causes the 85 bent portion 49 of the spring to exert pressure upon the leaves as shown.

The enlarged end cap 67 in Figure 16 aids in maintaining this pressure.

As illustrated in Figures 1 to 8 inclusive, a U-shaped cover 31 is provided for each post end. The cover is pivoted within the upper binding bar at 41, just above the opening 23 through which the post enters the bar. The cover 31 is pivoted in an inverted U-bar 42 (Fig. 8), whose web is notched at 43 to coincide with the edge of the lower wall of the clamping bar where it is perforated at 23. The secured end of plate spring 39 may be shaped to lie between the web of the U-bar 42 and the lower wall of the clamping bar, in which case this spring is perforated at 44 to coincide with the opening 23 and the notch 43. The cover and spring are then secured to the clamping bar by any suitable means such as a rivet 45.

At the center of the clamping bar is provided a spring-operated latch 46, which catches and holds the detent 47 on the free end of the cover 31 when the latter is swung down into the clamping bar 22.

To unlock the cover, the operator pushes transversely of the clamping bar upon the surface 48 to which latch 46 is fastened, thus releasing the latch against the spring pressure.

Covers of different form or arrangement may be provided. A modified form of cover is shown in Figure 10, pivoted near the center of the bar and latched near the point where the post enters the binding bar.

In Figure 9 a modification is shown in which the whole post is yieldingly secured in the lower clamping bar, a coiled spring 52 being provided to aid in clamping upon the sheets by taking up the slack between the clamping bars when the slack is less than the height of any one sleeve. In this form, a bushing 53 within which the post rides, is provided for the opening in the upper wall 130

of the lower clamping bar. A plate 54 is provided (see also Figure 10) of suitable length to lie loosely over the lower wall of the lower clamping bar. A section 55 of each post is secured to the plate 54 by means of a screw 56, the head of which lies in an opening in the lower wall of the lower clamping bar. The lower end of the spring 52 presses against the plate 54, while the upper end of the spring presses against the top wall of the clamping bar. The flexible member 24 is clamped by a screw into a lower end section 57 which forms part of the outside of the post, and is preferably of the same external diameter as the sleeves. If it is desired to have an extensible, rigid portion in the post, any number of rigid extension units of known construction may be inserted in the post between the section 55 and the end section 57 which latter acts as a connecting section between the rigid and flexible portions of the post. Such a rigid extension unit is shown at 58 (Fig. 9). As illustrated in Figure 9, the top of the end section 57 is formed with a neck like that on the sleeves 25 in order to nest in a flange of the sleeve above it. It is obvious that if the sleeves were threaded upon flexible element in reverse position, as in Figures 1 and 10, the top of the lower end section 57 would be provided with a flange instead of a neck. Similarly, top end section 59 in Figure 9 has at its lower end a flange like that of the sleeves, instead of the neck shown on the top end section 35 in Figure 1.

Figure 10 shows a modification in which a spring associated with the lower end of the post acts to exert the tension upon the sleeves required to hold the post normally rigid.

In this form, reversing the arrangement shown in the other figures, the flexible member is fixedly secured to outer elements of the post at the free end of the post, while the spring which exerts tension on the sleeves is at the end of the post which is fixed to a clamping bar. The upper end of flexible member 24 is provided with an extension member 72, which is screwed into a top end section 69 and an end cap 70.

A blade spring 60 is placed in the lower clamping bar above a movable plate 54. The lower end of the flexible member is passed through the spring 60 and plate 54, and retained by means of a head 61 formed on the end of the flexible member below the plate.

In the drawings the head 61 is illustrated as formed on an extension piece 71, but obviously the head could be formed on the flexible member in other ways. It is also obvious that a coiled spring such as that shown at 52 in Fig. 9, could be used instead of the blade spring 60.

The pressure of the spring against the upper wall of the lower clamping bar pulls the flexible element downward and keeps the sleeve elements nested under pressure until the

operator pulls on the upper end of the post. The extension member 71 of the flexible element rides within a bushing 62 secured in the upper wall of the lower clamping bar. Bushing 62 forms the lower end of the outside of the post. The upper end of bushing 62 may be formed to cooperate with the lowest detached sleeve. The bushing may be made in more than one part, if desired.

In the modification shown in Figures 15 to 18 inclusive, a bushing 63 is provided in the lower clamping bar, into which the whole post is screwed by means of threads provided on lower end section 64. A modified flexible element is shown in Fig. 18, in the form of a link chain 29. The flexible element 29 is secured in the lower end section 64 by any suitable means such as a pin 65. The upper end of the section 64 forms part of the outside of the post and is shaped to interfit with one end of a sleeve. The upper end section 66 is shaped at its lower end to interfit with the other end of a sleeve. In this form, end cap 67, which screws on to the upper end element of the post, is made of larger diameter than the rest of the post and larger in diameter than the opening 23 in the bottom wall of the upper clamping bar. This enlarged cap prevents accidental removal of the upper clamping bar. In order to remove the clamping bar, the cap must first be removed, as shown in Figure 17. This construction is especially suitable when sheets notched to the edge are used.

The operation of the post has been described above. The spring means associated with an end of the post exerts pressure upon the sleeves or independent elements and holds the post normally rigid. The interfitting or nesting of the detached sleeves prevents offsetting between them and causes the post to present a smooth exterior.

I claim:

1. A post for loose leaf binder comprising a flexible member and a plurality of interfitting members threaded thereon and permitting the post to flex between them, in combination with spring means adapted to hold said post normally rigid by pressing upon said interfitting members.

2. A post for loose leaf binder comprising a flexible member and a series of independent interfitting sleeves threaded thereon, and permitting the post to flex in all directions between adjacent sleeves.

3. A post for loose leaf binder comprising a flexible member and a series of independent interfitting sleeves threaded thereon and permitting the post to flex in all directions, in combination with spring means to hold said post normally rigid by pressing upon said sleeves.

4. A post for loose leaf binder comprising a flexible member and a plurality of interfitting sleeves threaded thereon, in combina-

tion with spring means adapted to hold said post normally rigid, by pressing upon said sleeves each sleeve having a neck at one end and a flange at the other end to receive the 5 neck of the succeeding sleeve.

5. A flexible post for a loose leaf binder comprising a flexible member and a plurality of interfitting members threaded thereon, in combination with spring means adapted to hold said post normally rigid, by pressing upon said interfitting members each interfitting member having a neck at one end and a flange at the other end, the inner walls of the neck end tapering toward the outer 10 edge, to facilitate bending of the flexible member.

6. A flexible post for a loose leaf binder comprising a flexible element, a plurality of interfitting members threaded thereon forming part of the outside of the post, and upper and lower end elements forming parts of the outside of the post, one of said end elements being associated with an end of the flexible element, in combination with spring means 20 to hold said post normally rigid by pressing upon said interfitting members.

7. A post for a loose leaf binder comprising a flexible element, a plurality of interfitting members threaded thereon and forming parts of the outside of the post, one end of the flexible member being secured to a part of the outside of the post adjacent one end of the post, in combination with spring means connected with said flexible member 30 adjacent the other end of the post and exerting tension upon the interfitting members to hold said post rigid.

8. A post for a loose leaf binder comprising a flexible element, a plurality of interfitting members threaded thereon and upper and lower end elements, said interfitting members and end elements forming parts of the outside of the post, in combination with spring means, one end of the flexible member 40 being secured in one end element, and the spring exerting tension between the other end of the flexible member and the other end element.

9. A post for loose leaf binder comprising a flexible element, a plurality of interfitting members threaded thereon and upper and lower end elements, in combination with spring means adapted to hold said post normally rigid by pressing upon said interfitting members, said interfitting members and end elements forming parts of the outside of the post and an end of each end element being formed to interfit with said interfitting members.

60 10. A flexible post for loose leaf binder comprising a flexible member and a plurality of independent interfitted elements threaded thereon, in combination with spring means adapted normally to hold the independent 65 elements interfitted, by pressing upon said

elements but permitting said post to bend between said independent elements when pressure is exerted against said spring.

11. In a loose leaf post binder having a 70 clamping bar, a post comprising a flexible member and a plurality of interfitting members threaded thereon, in combination with spring means adapted to hold said post normally rigid, by pressing upon said interfitting members said post being vertically yieldingly secured in the clamping bar.

12. In a loose leaf post binder having a 75 clamping bar, a plate lying in the clamping bar, and a flexible post secured in said clamping bar, said post comprising a flexible member 80 associated with said plate and a plurality of interfitting members threaded upon the flexible member, in combination with spring means associated with said plate and said flexible member within the clamping bar and exerting pressure on said interfitting members.

13. In a loose leaf post binder having a 85 clamping bar, a flexible post comprising a flexible member and a plurality of interfitting members threaded thereon, in combination with means securing said flexible member vertically yieldingly in the clamping bar.

14. In a loose leaf post binder having a 90 clamping bar, a post secured therein comprising a flexible member and a plurality of interfitting members threaded thereon, in combination with spring means associated with the flexible member adjacent the secured end of said post and adapted to hold 95 said post normally rigid by exerting pressure on the interfitting members.

15. In a loose leaf post binder having a 100 clamping bar, a post comprising a flexible member and a plurality of interfitting members threaded thereon, in combination with spring means within said clamping bar associated with an end of said flexible member adapted to hold said post normally rigid.

16. In a loose leaf post binder having upper and lower clamping bars, a flexible post comprising a flexible member and a plurality of interfitting members threaded thereon, in combination with spring means adapted to 110 hold said post normally rigid by pressing upon said interfitting members, but permitting said post to bend between said interfitting members when pressure is exerted against said spring, said post being secured 115 in said lower bar and passing through said upper clamping bar and the latter being adapted to receive the upper portion of the post when the post is flexed.

17. In a loose leaf binder having a hollow 120 upper clamping bar perforated to admit a post, cover means associated with said clamping bar, in combination with a post comprising a flexible member, a plurality of interfitting members threaded thereon forming 125 130

part of the outside of said post and allowing same to bend between said interfitting members, and to lie with its end buried in said upper clamping bar, and spring means adapted to hold said post normally rigid, said cover means comprising a U-shaped element pivoted adjacent the entrance of the post into the upper clamping bar, and having a spring operated latch at the center of said clamping bar.

18. In a loose leaf binder having a hollow upper clamping bar perforated in its lower wall to receive a post and to admit a spring, a post comprising a flexible member and a plurality of interfitting members threaded thereon, in combination with a spring to press upon sheets secured within said clamping bar and protruding through one of said perforations in the lower wall thereof.

19. In a loose leaf binder having a hollow upper clamping bar perforated in its lower wall to receive a post and to admit a spring, a flexible post in combination with a flat spring to press upon sheets having one end secured within said clamping bar, the other end resting freely within said clamping bar, and the intermediate bent portion projecting below said clamping bar through said latter perforation therein.

20. In a loose leaf binder having a hollow upper clamping bar perforated in its lower wall to receive a post and to admit a spring, a flexible post in combination with a flat spring to press upon sheets having one end secured within said clamping bar, the other end resting freely within said clamping bar, and the intermediate bent portion projecting below said clamping bar through a perforation therein, a portion of said post being adapted to lie buried in said clamping bar, and cover means on said clamping bar adapted to press the free end of said post against said spring.

21. In a loose leaf binder having a hollow upper clamping bar perforated in its lower wall to receive a post and to admit a spring, a flexible post comprising a flexible member and a plurality of sleeves threaded thereon, in combination with a flat spring to press upon sheets having one end secured within said clamping bar adjacent the entrance of the post into said bar, the other end resting freely within said clamping bar, and the intermediate bent portion projecting below said clamping bar through said latter perforation therein.

22. In a loose leaf binder having an upper clamping bar perforated to receive a post and to admit a spring, a flexible post having an enlarged end cap in combination with a flat spring having one end secured within said clamping bar, the other end resting freely within said clamping bar, and the intermediate bent portion projecting below said

clamping bar through a perforation therein, and cover means on said clamping bar adapted to press enlarged end cap upon the free end of said spring.

In testimony whereof I have signed my 70 name to this specification.

EDMOND G. DUPRÉE.
